Application May 8, 1952, Serial No. 286,735

8 Claims. (Cl. 259—104)

The present invention relates to mixing machines, and particularly to material mixers adapted for industrial uses.

Many industrial processes involve the mixing or working of materials for the purpose of producing greater homogeneity or of insuring that a chemical or physical reaction occurs uniformly throughout a given mass of the material. Since the viscosity and other characteristics of the materials which must be dealt with vary widely, it is a common experience to find that a given material cannot be satisfactorily mixed by a type of mixer which may be the most efficient for mixing another material. Moreover, some materials may be mixed by a wide variety of types of mixers, while other materials which are more difficult to mix can only be mixed by a few or only a single known type. Frequently different materials in this class require different types of mixers. Finally, there are some materials, such as chicle (which must be thoroughly worked during a washing operation), ethocell emulsions, some pigments, resins and other materials which are very difficult to deal with in any previously known type of mixing machine, since they require prolonged mixing treatments and frequently necessitate high expenditures of power. There is a need, therefore, for a heavy-duty mixer which will operate efficiently and effectively on a number of the materials which are difficult to mix.

The general class of mixers which have been used most extensively on materials that are difficult to work or mix are those in which the mixer comprises a suitable housing having a pair of oppositely rotating shafts equipped with mixing blades. The blades are so arranged that any single transverse plane intersects two blades on each shaft, and the blades of each shaft in that plane are diametrically opposed to each other. Three types of mixers within that general class have been used, as follows: first, those in which the blades on the two shafts overlap (i. e. are longer than one half the distance between the shafts) and the shafts rotate at the same speed (see U. S. Patent No. 1,563,524); second, those in which the blades do not overlap and the shafts are rotated at any desired different speeds (see U. S. Patents Nos. 1,364,401 and 1,989,126); and third, those in which the blades overlap and one shaft rotates at exactly twice the speed of the other (see U. S. Patents 1,004,908 and 2,095,907. Patent 913,133 discloses a similar mixer except that one blade is omitted on one shaft.)

Another general class of mixers which have been used have overlapping blades on parallel shafts with four blades on each shaft in a single transverse plane. In this class of mixer the shafts always rotate at the same speed. They do not provide as effective a mixing action on heavy materials as do mixers in which the speeds of the shafts differ, and the permissible amount of blade overlap is somewhat restricted.

A third classification of prior mixers comprises a mixer having two diametrically opposed blades on one shaft and four equally spaced blades on the other, with the two bladed shaft rotated at twice the speed of the four bladed

2

shaft. The blades fully overlap. This type of mixer performs an effective mixing function but requires a substantial power input.

It has been observed that overlapping blades provide enhanced mixing and that some difference in the speeds of the shafts also aids in the performance of the mixing function. However, if the difference in speeds is as much as two to one, the power requirements of the mixer are substantially increased, all other things being equal. It has also been recognized that within limits an increase in the number of blades increases the mixing action but also the power requirements; and an increase in the number of blades tends to reduce the permissible amount of blade overlap.

It is the general object of the present invention to provide a fourth class of mixer which will achieve the optimum of mixing effect for a given power expenditure and which is peculiarly suited for use on chicle and other materials which are difficult to mix. This objective is realized by employing the maximum number of blades which will overlap to the maximum extent with a relatively small difference between the speeds of the two shafts. More specifically, the arrangement involves the use of two diametrically opposed blades on one shaft and three equally spaced blades on the other, with the two bladed shaft driven at one and one half times the speed of the three bladed shaft. It is found that such a mixer may be used successfully on a wide variety of materials which are difficult to mix; will mix some materials that cannot be mixed by either of the first two classes of mixers referred to above; and requires substantially less power than the third class of mixer mentioned for an equivalent mixing job.

The blades closely fit the bottom and end walls of the housing to avoid the formation of pockets or layers of material which might not be acted on by the blades. For the same reason, the blades overlap each other to such an extent that the outer edges of the blades on one shaft pass close to the other shaft. As a result of this arrangement and the fact that the shafts are moving at different speeds, material is trapped between adjacent blades and between the blades and the bottom of the housing and is subjected to a squeezing action. This squeezing action will tend to extrude the trapped material through the running clearances at the ends of the blades and the ends of the housing, but since these clearances are preferably made as small as possible, heavy materials cannot escape with the required rapidity and hence excessive pressures will develop and it will be substantially impossible to drive the mixer at a useful speed. While this difficulty may be overcome by providing notches in the ends of the blades, the notches in each blade being displaced axially with respect to the notches in other blades on the same shaft, it is preferred to provide openings in the blades themselves. The extrusion of the material through these openings during the mixing operation greatly enhances the mixing function and constitutes a major factor contributing to the improved efficiency of the mixer.

The blades are preferably curved forwardly at their outer extremities to resist the natural tendency of the material to slide outwardly along the faces of the blades. This also provides a hooking action which will draw material down between the two shafts.

In the preferred embodiment of the invention shown, three axially spaced sets of blades are provided within the housing. The two sets at the ends of the housing have blades which are so inclined with respect to the axes of the shafts that they tend to feed material toward the center of the housing. This enhances the mixing action.

Other objects, features, and advantages of the present

invention will become apparent from the subsequent description, taken in conjunction with the accompanying drawings.

In the drawings: ~~the drawings will stand off~~ Figure 1 is a side elevational view of the mixer, showing the supporting base and the driving motor;

Figure 2 is an end elevational view of the apparatus of Figure 1 with the end guard plate removed, and showing the tilting mechanism;

Figure 3 is a cross-sectional view taken along the line 3-3 of Figure 2, and showing the mixer blades and the supporting means for the blade shafts;

Figure 4 is a cross sectional view taken along the line 4-4 of Figure 3 and showing the configuration of the central sets of blades; and

Figure 5 is a cross-sectional view taken along the line 5-5 of Figure 3 and showing the configuration of the outer sets of blades.

The mechanism comprises in general a container or trough 11 for holding the batch of material to be mixed, a supporting stand 12 supporting the trough assembly for pivotal movement about a horizontal axis, and a driving motor 13 supported on a base 14 and operatively connected to the blade shafts. The trough 11 comprises an inner wall 15 of generally U-shaped cross-section and an outer shell 16 which surrounds the inner wall, forming a jacket 17 therebetween to hold a cooling medium or the like. In the illustrated embodiment, the outer shell 16 is joined with wall 15 along its upper edges 18 and side edges 19, and the jacket is provided with a drain opening 20. The ends of trough wall 15 are closed by end plates 21 and 22 which are secured thereto by means of flanges 23 and 24 at the opposite ends of wall 15.

The trough 11 is supported at the opposite ends by a pair of bearing supports 25 and 26 which extend upwardly from base 12. These bearing supports are provided with bearings 27 and 28 respectively at their upper ends, and a pair of trunnions 29 and 31 are secured to the opposite ends of trough 11 and are journaled within these bearings. Trunnion 29 is secured outwardly of end plate 21 by a bracket structure 32, and trunnion 31 is secured to the outer end of a gear housing 33 which in turn is supported by the trough. Housing 33 is secured to the end plate 22 through the intermediary of a bearing supporting framework 34 which is secured to and extends from end plate 22. As will be seen later, bearing support 34 serves to hold the bearings for the blade shafts.

The trunnions 29 and 31 are annular in shape and serve as bearing supports for a blade shaft 35 which extends through the trough and serves to support the front blades therein. In particular, the opposite ends of shaft 35 are provided with bushings 36 and 37 which are disposed within trunnions 29 and 31 respectively, so that the shaft is freely rotatable independently of the position of the trough. The end of shaft 35 adjacent bearing support 26 is connected to driving motor 13 through a coupling 38.

Means are provided for tilting the trough assembly for receiving or dumping material, and this means preferably comprises a worm gear quadrant 39 keyed to trunnion 29 outwardly of bearing 27. A guard 40 supported by base 12 is provided to cover the worm gear quadrant 39 and its adjacent parts. A worm 41 is supported on base 12 by means of bearings 43 and 44 for rotation about a horizontal axis, this worm meshing with worm gear quadrant 39, and a hand crank 45 allows the worm to be rotated, thus rocking the entire trough about the axis of shaft 35. A stop 46 may be provided on the base for positioning the trough.

The trough is also provided with a second shaft 47 parallel to shaft 35 for supporting the rear blades. Shaft 47 is supported at its opposite ends by bearings 48 and 49, bearing 48 being secured outwardly of the trough by means of bracket structure 32. Bearing 49 is supported

by bearing support 34, this bearing support also supporting an intermediate bearing housing 52 for shaft 35.

In order to take the axial thrust loads which the shafts 47 and 35 are subjected to during operation, these shafts 5 are provided with thrust plates secured to one end thereof. In particular, shaft 35 is provided with a thrust plate 53 secured to one end by means of bolts 54, this plate being disposed within a recess at the end of trunnion 29 and held in place by an end cap 55. Shaft 47 is likewise provided with a thrust plate 56 disposed within a recess in bearing 48 and held in place by a cap 57. In order to prevent leakage of the material from the trough, glands 58 are provided on shafts 35 and 47 secured to the trough end plates 21 and 22. In Figure 3, the glands 58 on the left hand side are shown in vertical cross-section to make visible their attaching bolts 59.

As stated previously, motor 13 is coupled to front blade shaft 35 and this shaft is provided with a gear 61 within gear housing 33. Gear 61 meshes with a gear 62 secured to the end of rear shaft 47 within the gear housing. These gears may be conventional spur gears, and the ratio of their teeth is such that shaft 47 makes one and one half revolutions per revolution of shaft 35. Of course, other types of gearing may be used if desired to achieve this ratio.

The sets of blades are best shown in Figures 3, 4 and 5, and in the illustrated embodiment the blades on shaft 35 are termed the front blades and the blades on shaft 47 the rear blades. It will be seen that in the illustrated embodiment each shaft has three sets of blades; in particular, front shaft 35 has a central set of blades 63 and an outer set of blades 64 on either side thereof, and shaft 47 is provided with a central set of blades 65 and an outer set of blades 66 on either side thereof. As seen in Figures 4 and 5, the blade sets are preferably provided with hubs which are keyed to shafts 35 and 47. Blade set 63 comprises a pair of diametrically opposed blades 67, while blade set 65 on shaft 47 comprises three equally spaced blades 68. Preferably, these blades are curved slightly forward at their outward portions in the direction of rotation; that is, blade 67 is curved slightly clockwise and blades 68 slightly counterclockwise as shown in Fig. 4. Blades 67 and 68 are preferably aligned in an axial direction with the axes of their respective shafts, and the blades are so positioned on the shafts that, as seen in Fig. 4, when a particular blade 68 lies substantially on a line intersecting the shaft axes, blades 67 will be substantially perpendicular to this line. It will be seen that since shaft 35 rotates at one and one half times the speed of shaft 47, the blades 67 will pass between the blades 68 during operation, while moving at a faster rate than blades 68.

The blade sets 64 on shaft 35 and the blade sets 66 on shaft 47 are each symmetrically disposed about their respective central blade sets, but are offset from the central sets in a circumferential direction. Each blade set 64 comprises two diametrically opposed blades 69, and each blade set 66 includes three equally spaced blades 71. Like the central blades 67 and 68, blades 69 and 71 are also curved forwardly at their outer ends as shown in Figure 5. However, these blades are of skew shape with respect to their shafts, so that the outer edges 72 of blades 69 and the outer edges 73 of blades 71 form portions of helices around their shaft axes. These shapes, during rotation of the shaft blade sets 64 and 66, will tend to force the material from the end plates 21 and 22 of the trough toward the central portion of the trough.

Preferably, the clearance 74 between the ends of blade sets 64 and 66 and the end plates 21 and 22 of the trough are so small that little material can be forced between the end plates and the blade ends. The bottom of trough 15 is of a doubly curved shape to conform to the path of the blades. In particular, the trough bottom is provided with a concave portion 75 concentric with the axis of shaft 35, and a concave portion 76 concentric with the

axis of shaft 47. The clearances between the edges of the blades and the curved portions 75 and 76 are so small as to prevent the formation of pockets or layers of material which may not be acted upon by the blades. The blade widths are such, relative to the distance between shafts 35 and 47, that the blades overlap to a considerable extent, the outer edges of the blades on one shaft passing close to the hub of the blades on the other shaft.

In order to prevent excessive pressure between the blades during operation, each blade is preferably provided with an opening 77 through which the material trapped between adjacent blades may pass. It will be appreciated that since the shafts are moving at different speeds, material trapped between adjacent blades and between the blades and the housing are subjected to a squeezing action and that heavy materials cannot escape between the blade ends and the walls of the trough because of the small clearances. The extrusion of the material through openings 77 therefore greatly improves the efficiency of the mixer especially when used with heavy materials. Although the openings 77 are shown as rectangular in shape in the illustrated embodiment, other shapes of openings may of course be used.

In operation, the material to be mixed is placed in the trough, and if necessary the blades may be jogged back and forth in order to allow the material to settle more compactly in the trough. The motor 13 is then started, driving shafts 35 and 47 in opposite directions as seen in Figures 4 and 5, shaft 35 running at one and one-half times the speed of shaft 47, and blade sets 63 and 64 on shaft 35 will cooperate with blade sets 65 and 66 on shaft 47 to mix the material. The blade sets will move in the direction of the arrows in Figures 4 and 5, with the blades moving downwardly between the shafts. Since front shaft 35 is rotating at a higher speed than rear shaft 47, as each front blade passes between two rear blades, it will force the material ahead of it against the back surface of a rear blade. At the same time, the skew shaped side blades will continuously circulate material from the sides to the central portion of the trough. In this manner a thorough and efficient mixing action takes place between the blades.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. A mixer having a housing, a pair of parallel shafts journaled in said housing, and mixing blades on said shafts, there being in a single transverse plane two generally radial and diametrically opposed blades on one of said shafts and three equally spaced generally radial blades on the other, the radial length of each of said blades being sufficient to cause the blades to overlap and their outer edges to sweep in close proximity to the hub of the blades on the other shaft, and means for rotating said shafts in opposite directions with the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts.

2. A mixer having a housing, a pair of parallel shafts journaled in said housing, and mixing blades on said shafts, there being in a single transverse plane two generally radial and diametrically opposed blades on one of said shafts and three equally spaced generally radial blades on the other, the radial length of each of said blades being sufficient to cause the blades to overlap and

their outer edges to sweep in close proximity to the hub of the blades on the other shaft, and means for rotating said shafts in opposite directions with the blades on both shafts moving downwardly between the shafts and the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts.

3. A mixer having a housing, a pair of parallel shafts journaled in said housing, and mixing blades on said shafts, there being in a single transverse plane two generally radial and diametrically opposed blades on one of said shafts and three equally spaced generally radial blades on the other, the radial length of each of said blades being sufficient to cause the blades to overlap and their outer edges to sweep in close proximity to the hub of the blades on the other shaft, and means for rotating said shafts in opposite directions with the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts, the bottom of said housing being formed to lie in close proximity to the paths of movement of said blade tips below the plane common to said shafts.

4. A mixer having a housing, a pair of parallel shafts journaled in said housing and mixing blades on said shafts, there being in a single transverse plane two generally radial and diametrically opposed blades on one of said shafts and three equally spaced generally radial blades on the other, the radial length of each of said blades being sufficient to cause the blades to overlap and their outer edges to sweep in close proximity to the hub of the blades on the other shaft, and means for rotating said shafts in opposite directions with the blades on both shafts moving downwardly between the shafts and the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts, the bottom of said housing being formed to lie in close proximity to the paths of movement of said blade tips below the plane common to said shafts.

5. A mixer having a housing, a pair of parallel shafts journaled in said housing, and mixing blades on said shafts, there being in a single transverse plane two generally radial and diametrically opposed blades on one of said shafts and three equally spaced generally radial blades on the other, the radial length of each of said blades being sufficient to cause the blades to overlap and their outer edges to sweep in close proximity to the hub of the blades on the other shaft, and means for rotating said shafts in opposite directions with the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts, the bottom of said housing being formed to lie in close proximity to the paths of movement of said blade tips below the plane common to said

shafts, said blades having openings therein through which material may extrude during the mixing operation.

6. A mixer having a housing, a pair of parallel shafts journaled in said housing, and mixing blades on said shafts, there being in a single transverse plane two generally radial and diametrically opposed blades on one of said shafts and three equally spaced generally radial blades on the other, the radial length of each of said blades being sufficient to cause the blades to overlap and their outer edges to sweep in close proximity to the hub of the blades on the other shaft, and means for rotating said shafts in opposite directions with the blades on both shafts moving downwardly between the shafts and the speed of the two bladed shaft one and one half the speed of the three bladed shaft, said blades being so fixed on said shafts and the shafts so interconnected that in said transverse plane the radial line of a blade on the two bladed shaft is substantially perpendicular to the line intersecting the axes of the two shafts when the radial line of one of the blades of the three bladed shaft lies approximately in the line intersecting said shafts, the bottom of said housing being formed to lie in close proximity to the paths of movement of said blade tips below the plane common to said shafts, said blades having openings there- 15 in through which material may extrude during the mix- 25 ing operation.

7. A mixer as defined in claim 1 in which there are two sets of cooperating blades on said shafts, one set being located at each end of said shafts and each set being identical except that the blades are inclined with respect to the axes of the shafts so that the blade tips lie in a helix with the helix angle of one set opposite to that of the other and the angular position of the blades tends to work material away from the ends of the shafts.

8. A mixer as defined in claim 7 in which there is a third set of cooperating blades on said shafts disposed between said first two sets, the blades of said third set lying in planes substantially parallel to their respective shaft axes.
